UNITED STATES PATENT OFFICE.

WILLIAM GENTRY SHELTON, OF NEW YORK, N. Y.

STIRRER.

1,317,228.

Specification of Letters Patent. Patented Sept. 30, 1919.

Continuation in part of application Serial No. 254,541, filed September 18, 1918. This application filed January 29, 1919. Serial No. 273,726.

To all whom it may concern:

Be it known that I, WILLIAM GENTRY SHELTON, a citizen of the United States of America, residing in the borough of Manhattan, city, county, and State of New York, have invented certain new and useful Improvements in Stirrers, of which the following is a specification.

This invention relates to stirrers, particularly of the kind used upon counters of soda fountains for mixing drinks, and aims to provide improvements therein.

This application is a continuation in part of my application Serial No. 254,541, filed September 18, 1918.

The invention provides a device of great simplicity, and embodying therein a number of desiderata, as regards its serviceability and convenience of use. Sliding parts necessary to bring the stirrer into or out of position in the glass are avoided. The device is so constructed that the stirrer, and its support, and its motor, which is usually employed, move around a single pivotal axis in order to bring the stirrer into or out of the glass. The pivotal arrangement is such that the stirrer may be moved into and out of deep, narrow glasses resting upon a platform or support, and which permits of the immediate placing of the glass beneath the stirrer, when the latter is in its withdrawn position. The arrangement is also such that the stirrer and its support, in its withdrawn position, will remain in a stable position with the end of the stirrer pointing downwardly, with its end over the top of the glass, in such manner that the liquid thereon may drip back into the glass when the stirrer is lifted. The stirrer is also so mounted that deformations thereof will not produce a violent movement when it is rapidly rotated.

The stirrer is usually driven by an electric motor and this motor and stirrer are mounted as a removable unit in the stirrer support.

A preferred embodiment of the invention is illustrated in the accompanying drawing.

Said drawing illustrates in Figure 1 the invention in side elevation. Figs. 2 and 3 are elevations at 90° to each other, and partly in section, illustrating the resilient mounting of the motor.

In said drawing, numeral 1 designates a

stirrer of any suitable construction carried by an arm or support 2. The arm or support 2 is pivotally mounted as indicated at 3, the support 2 being conveniently mounted upon a bracket or post 4 attached to a base 5, or directly to a counter or the like. The glass containing the drink or substance to be mixed rests beneath the stirrer upon the base 5 or other part. Spring clips 6 may be provided for locating and holding the glass in proper position.

The stirrer is preferably directly driven by an electric motor 7, the motor and stirrer preferably being formed as a unit, the two, however, being conveniently connected by a socket or coupling piece 8. Furthermore, the pivoted support 2 is preferably formed with bifurcated arms 9 through the ends of which pass screws or the like 10 which serve to removably hold the motor and attached stirrer in place.

The pivotal axis 3 is preferably located somewhat above the base or part upon which rests the glass, in such manner that the arc 12 through which the end of the stirrer 1 moves, is substantially vertical. Preferably, the pivotal axis is about midway of the height of the glass above the base or part on which it rests.

The pivotal axis is also preferably sufficiently to one side of the axis of the stirrer, so that the arc 12 is a relatively flat one.

The arm or support 2 and the mounting or post 4 are preferably formed with complementary front and back stops 13 and 14. These stops are so arranged that when the arm 2 with the stirrer 1 is in the forward position with the stirrer in place within the glass, that the stirrer stands substantially vertical therein. The back stops 13 are preferably so arranged that when the arm 2 and attached stirrer 1 are in the raised or withdrawn position, the stirrer points downwardly with its end over the top of the glass, in such manner that liquid thereon may run down the stirrer and drip off of its end back into the glass. Moreover, the arrangement is such that when the arm 2, and the parts carried thereby, is in either its stirring or raised position, resting upon either the stops 13 or 14, the center of gravity of the arm 2 and parts carried thereby, is to one side or the other of a line passing vertically through the pivotal axis 3, whereby the arm 2 and

parts carried thereby are in stable equilibrium in either its stirring or raised position.

As the stirrer 1 is long and unsupported at its lower end, its lower end usually vibrates when the stirrer is lowered into the glass, and when the stirrer begins to rotate.

The result is that the stirrer does not rotate on its true axis when the motor is started, but has a pendulous motion along with its rotary movement, which produces a chattering noise, an undesirably rough motion and an undesirable strain upon the parts. These objections are overcome by resiliently mounting the motor in the support 2, preferably by placing soft rubber bushings 15 between the screws 10 and the arms 9. These bushings 15 are conveniently of the form shown, having an annular indentation or recess 16 and projecting portions 17 on either side thereof which embrace the edges of the arms 9 around the holes 18 therein. A similar bushing 20 is preferably placed between the motor and support 2 midway between the axis of the screws 10, 10. This bushing 20 may conveniently fit in a recess 21 in the motor casing and an opposite recess 22 in the support 2. The electrical feed wires may be led through this bushing 20 to the terminals of the motor. When thus resiliently mounted, the movement of the stirrer rapidly settles down to a true and easy rotation around the axis of the stirrer.

Moreover, if the stirrer becomes "sprung" so that it is not perfectly true, which is the rule rather than the exception, in practical use, the movement becomes so violent as to be very objectionable, unless provided with a means as described above for resiliently carrying the motor casing or other support of the stirrer.

The operation and manipulation of the device is extremely simple. It is simply necessary to place a glass upon the base 5 or corresponding part, and throw the arm 2 carrying the stirrer forward. The motor may be started either automatically or by a hand-operated switch. When the stirring has been completed, it is simply necessary to throw the arm 2 up and backwardly until it comes to rest with the stops 13 in contact. The parts remain in stable position with the stirrer pointed downward and its end over the top of the glass in such a manner that liquid thereon may run and drip back into the glass. The glass may be immediately removed and another substituted, in order to repeat the stirring operation.

To repair or replace the motor, it is simply necessary to loosen the screws 10 and remove and replace it.

What I claim is:—

1. A counter stirring device for liquids, comprising a stirrer, a motor for driving

the stirrer and a pivoted support carrying said motor and stirrer, whereby said stirrer may be moved into and out of a glass, said support and parts carried thereby having their center of gravity movable to either side of a vertical line passing through the pivotal axis of the pivoted support, said pivotal axis being approximately midway of the height of a glass, which is approximately twice the height of said pivotal axis, and means against which said stirrer may rest, with its end pointing downwardly, when withdrawn from the glass.

2. A counter stirring device for liquids, comprising a stirrer, a motor for driving the stirrer and a pivoted support carrying said motor and stirrer, whereby said stirrer may be moved into and out of a glass, said support and parts carried thereby having their center of gravity movable to either side of a vertical line passing through the pivotal axis of the pivoted support, said pivotal axis being approximately midway of the height of a glass, which is approximately twice the height of said pivotal axis, and means against which said stirrer may rest, with its end pointing downwardly, when withdrawn from the glass.

3. A counter stirring device for liquids, comprising a stirrer, a pivoted support therefor, whereby said stirrer may be moved into and out of a glass, said pivotal axis being approximately midway of the height of a glass, which is approximately twice the height of said pivotal axis.

4. A counter stirring device for liquids, comprising a stirrer, a motor and a pivoted support carrying said stirrer and motor, whereby said stirrer may be moved into and out of a glass, said pivotal axis being approximately midway of the height of a glass, which is approximately twice the height of said pivotal axis.

5. A counter stirring device for liquids, comprising a stirrer, a motor and a pivoted support carrying said stirrer and motor, whereby said stirrer may be moved into and out of a glass, said pivotal axis being approximately midway of the height of a glass, which is approximately twice the height of said pivotal axis, and means against which said stirrer may rest, with its end pointing downwardly, when withdrawn from the glass.

6. A counter stirring device for liquids, comprising a stirrer, a pivoted support therefor, permitting said stirrer to be moved into and out of a glass, said pivotal axis being approximately midway of the height of a glass which is approximately twice the height of said pivotal axis, and a stop for holding said stirrer in a downwardly pointed direction with its end over the glass, so that the liquid thereon may drip back into the glass.

the glass when the stirrer is lifted, said stirrer and support having their center of gravity behind the vertical plane passing through the pivotal axis when said stirrer is 5 in its lifted position, whereby the weight of said stirrer and support tends to keep said parts against said stop when in said lifted position.

height of said pivotal axis, a stop for holding said stirrer in a downwardly pointed direction with its end over the glass, so that the liquid thereon may drip back into the 55 glass when the stirrer is lifted, and a stop limiting the forward movement of the stirrer into the glass, said stirrer and support having their center of gravity behind the vertical plane passing through the pivotal 60 axis when said stirrer is in its lifted position, whereby the weight of said stirrer and support tends to keep said parts against said first-named stop when in said lifted position, said stirrer and support having their center 65 of gravity in front of said vertical plane passing through the pivotal axis when said stirrer is in its stirring position in the glass, whereby the weight of said stirrer and support tends to keep said parts against said 70 second-named stop when in stirring position.

7. A counter stirring device for liquids, 10 comprising a vertical stirrer, a pivoted support therefor, permitting said stirrer to be moved into and out of a glass, said pivotal axis being approximately midway of the height of a glass which is approximately twice the height of said pivotal axis when said stirrer is in its lifted position, whereby the weight of said stirrer and support tends to 15 keep said parts against said stop when in said lifted position.

7. A counter stirring device for liquids, 10 comprising a vertical stirrer, a pivoted support therefor, permitting said stirrer to be moved into and out of a glass, said pivotal axis being approximately midway of the height of a glass which is approximately twice the height of said pivotal axis when said stirrer is in its lifted position, whereby the weight of said stirrer and support tends to 15 keep said parts against said stop when in said lifted position.

7. A counter stirring device for liquids, 10 comprising a vertical stirrer, a pivoted support therefor, permitting said stirrer to be moved into and out of a glass, said pivotal axis being approximately midway of the height of a glass which is approximately twice the height of said pivotal axis when said stirrer is in its lifted position, whereby the weight of said stirrer and support tends to 15 keep said parts against said stop when in said lifted position.

8. A counter stirring device for liquids, 10 comprising a stirrer, a motor and a pivoted support carrying said stirrer and motor, permitting said stirrer to be moved into and out of a glass, said pivotal axis being approximately midway of the height of a glass which is approximately twice the height of said pivotal axis, and a stop for holding said stirrer in a downwardly pointed direction with its end over the glass, so that the liquid thereon may drip back into the glass when the stirrer is lifted, said stirrer and support having their center of gravity behind the vertical plane passing through the pivotal axis when said stirrer is in its lifted position, whereby the weight of said stirrer, motor and support tends to keep said parts against said stop when in said lifted position.

8. A counter stirring device for liquids, 10 comprising a stirrer, a motor and a pivoted support carrying said stirrer and motor, permitting said stirrer to be moved into and out of a glass, said pivotal axis being approximately midway of the height of a glass which is approximately twice the height of said pivotal axis, and a stop for holding said stirrer in a downwardly pointed direction with its end over the glass, so that the liquid thereon may drip back into the glass when the stirrer is lifted, said stirrer and support having their center of gravity behind the vertical plane passing through the pivotal axis when said stirrer is in its lifted position, whereby the weight of said stirrer, motor and support tends to keep said parts against said stop when in said lifted position.

8. A counter stirring device for liquids, 10 comprising a stirrer, a motor and a pivoted support carrying said stirrer and motor, permitting said stirrer to be moved into and out of a glass, said pivotal axis being approximately midway of the height of a glass which is approximately twice the height of said pivotal axis, and a stop for holding said stirrer in a downwardly pointed direction with its end over the glass, so that the liquid thereon may drip back into the glass when the stirrer is lifted, said stirrer and support having their center of gravity behind the vertical plane passing through the pivotal axis when said stirrer is in its lifted position, whereby the weight of said stirrer, motor and support tends to keep said parts against said stop when in said lifted position.

9. A counter stirring device for liquids, 10 comprising a stirrer, a pivoted support therefor, permitting said stirrer to be moved into and out of a glass, said pivotal axis being approximately midway of the height of a glass which is approximately twice the height of said pivotal axis when said stirrer is in its lifted position, whereby the weight of said stirrer and support tends to keep said parts against said stop when in said lifted position.

9. A counter stirring device for liquids, 10 comprising a stirrer, a pivoted support therefor, permitting said stirrer to be moved into and out of a glass, said pivotal axis being approximately midway of the height of a glass which is approximately twice the height of said pivotal axis when said stirrer is in its lifted position, whereby the weight of said stirrer and support tends to keep said parts against said stop when in said lifted position.

In witness whereof, I have hereunto signed 100 my name.

WILLIAM GENTRY SHELTON.
